UNITED STATES PATENT OFFICE.

JAMES M. LEAVER, JR., OF OAKLAND, CALIFORNIA.

AUTOMATIC BUNDLING AND TYING MACHINE.

1,295,531.

Specification of Letters Patent. Patented Feb. 25, 1919.

Application filed December 19, 1916. Serial No. 137,876.

To all whom it may concern:

Be it known that I, JAMES M. LEAVER, Jr., a citizen of the United States, residing at Oakland, in the county of Alameda and State of California, have invented a new and useful Automatic Bundling and Tying Machine, of which the following is a specification.

The invention relates to an automatic bundling and tying machine.

The object of the present invention is to improve the construction of bundling machines, and to provide an efficient and comparatively inexpensive machine, designed for bundling and tying cut lumber and various other materials, and capable of automatic operation to form bundles of uniform size, to bind the bundles with wire and tie the ends of the wire without overtaxing the wire or distorting the same or putting undue tension on any part of the band or knot so that the terminal strain will be not greater in the knot than elsewhere on the wire, and there will be no liability of weakening, breaking or twisting off the wire.

A further object of the invention is to provide adjustable mechanism for automatically engaging a predetermined number of pieces of material in a magazine, removing them therefrom and presenting them in bundle form to the binding means, and binding the material under a constant pressure and knotting the wire while the material is under the desired pressure without slackening or

loosening the bands, thereby insuring a compact and perfectly formed bundle when non-expansible or inelastic material is handled. It is also the object of the invention to enable the bundles to be tied with the desired number of bands the proper distance apart, and to bind and tie the bundles tightly without either drawing the wire over the material and injuring the same, or allowing any slack after the knot is tied, thereby making a firm, compact and strong bundle. Furthermore, the invention is designed to provide a machine in which no skill is required in tying the bundles and in which there will be no danger of breaking the wire by care-

less operation of the machine.

With these and other objects in view, the invention consists in the construction and

novel combination of parts hereinafter fully described, illustrated in the accompanying drawings, and pointed out in the claims 55 hereto appended.

In the drawings:

Figure 1 is a side elevation of an automatic bundling and tying machine, constructed in accordance with this invention, 60 and illustrating the initial positions of the parts.

Fig. 2 is a similar view of the opposite side of the machine, showing the material for forming bundles advanced from the 65 lower end of the magazine and partially bound.

Fig. 3 is a central longitudinal sectional view, illustrating another position of the mechanism, the bundle advancing means being returned to its initial position, and the stack of material within the magazine being supported in an elevated position.

Fig. 4 is a rear elevation of the machine.

Fig. 5 is a plan view of the machine, parts 75 being removed.

Fig. 6 is a transverse sectional view on the line 6—6 of Fig. 1.

Fig. 7 is a horizontal sectional view on the line 7—7 of Fig. 4.

Fig. 8 is a vertical longitudinal sectional view on the line 8—8 of Fig. 4.

Fig. 9 is a vertical longitudinal sectional view on the line 9—9 of Fig. 7, showing the inner face of one of the main cam wheels.

Fig. 10 is a similar view, taken on the same line as Fig. 9 but looking in the opposite direction and showing the inner face of the other main cam wheel.

Fig. 11 is an enlarged transverse sectional view on the line 11—11 of Fig. 8.

Fig. 12 is a plan view of the swinging frame and the tensioning or take-up lever.

Figs. 13 to 16 are detail elevations of the mechanism carried by the head of the wire 95 extension lever.

Fig. 17 is a vertical sectional view of the same.

Fig. 18 is a horizontal sectional view through the head end of the wire extension 100 lever.

Fig. 19 is an enlarged detail view partly in section, illustrating the construction of the wire coiling mechanism and the position

frames are adjustable by means of upper and lower right and left hand threaded screws 12 and 13, which, when operated by the means hereinafter described, move the 5 laterally adjustable frames simultaneously toward and from each other. The machine may be equipped with any number of sets of upper and lower auxiliary frames, but when three sets of such frames are employed, one 10 set will be located at the center of the machine and the central set of auxiliary frames will be stationary, and the side sets of auxiliary frames or supports will be adjustable toward and from the central set of auxiliary 15 frames or supports. The lower auxiliary frame of each set is provided at the bottom with spaced longitudinal channeled bars 14 and 15, see Figs. 3, 4 and 6 to 9, and at the top with a longitudinal channeled bar 15^a, located above and in substantially the vertical plane of the lower channeled bar 14 and connected with the same at the ends of the lower auxiliary frame by front and rear upright bars 16 and with 20 the ends of the other lower channeled bar 15 by inclined transverse braces 17. The lower channeled bars 14 and 15 are connected by transverse rods 18, arranged in pairs and secured to the channeled bars at the inner 25 faces thereof by screws 19, piercing the webs of the channeled bars 14 and 15 and engaging threaded sockets in the ends of the transverse rods 18, but any other suitable means may, of course, be employed for connecting 30 the channeled bars and for maintaining the same in spaced relation.

The longitudinal bars 14 and 15 of the lower auxiliary frame are slidably connected at their front and rear portions with the 40 bottom transverse beams 1 of the main frame by inner stops hereafter described and outer clamps 20, see Figs. 3 and 8, bolted to the bars 14 and 15 at the lower edges thereof and extending across the space between the 45 same and each provided with an upper recess 21 to receive the outer upper flange of the contiguous transverse beam 1 and extending beneath the said upper flange and equipped with an adjustable steel-plate 22, 50 which is forced into engagement with the lower face of the outer upper flange of the transverse beam by a set screw 23, mounted in a threaded opening 24 in the recessed projecting portion of the clamp 20. The 55 front inner stop 25, which is spaced from and co-operates with the front clamp, consists of a strip secured to the front portions of the channeled bars 14 and 15 and extending across the space between the same, and the 60 rear inner stops are preferably formed by spaced transversely aligned bearing blocks 26, secured to the bottom flanges of the bars 14 and 15 at the rear portions thereof. When it is desired to adjust the lower auxiliary 65 frame, the plates of the clamps are loosened

by unscrewing the set screws and after the proper adjustment is effected the set screws are tightened to cause the steel plates to grip firmly the bottom transverse beams of the main frame.

70

Each upper adjustable auxiliary frame or support is preferably composed of spaced longitudinally disposed angle bars 27, Figs. 1 to 5, connected at their rear portions by transverse plates or bars 28, which are secured to the horizontal wings or flanges of the angle bars 27 by vertical rods or bolts 29, piercing horizontal wings or flanges of spaced angle bars 30, arranged in pairs at opposite sides of the rear portion of the 80 upper auxiliary frame and forming horizontal guideways. The horizontal wings or flanges of the angle bars 30 of the guideways are spaced apart by sleeves 31, and the lower angle bars of the guideways are supported by vertical tubes 32. The sleeves and the tubes are arranged on the vertical rods or bolts 29, and the tubes are supported upon the horizontal flanges of the side angle bars 27 of the upper auxiliary frame and are 85 interposed between the same and the lower angle bars of the superimposed guideways, which extend longitudinally of the said upper auxiliary frame. The side bars of the upper auxiliary frame are also connected at their 90 front ends by a transverse plate or bar 33 (see Fig. 5) having a central vertical needle bar guide 34 and provided with terminal flanges, which are bolted to the vertical wings or flanges of the side bars 27. The 95 plate or bar 33 is preferably reinforced by a web or flange extending from the upper portion of the needle bar guide to the upturned upwardly extending terminal flanges, but the supporting portions of the needle 100 bar guide may be constructed in any other desired manner.

The upper auxiliary frame is slidably supported by the upper transverse main frame beams 11, fitting against the inner edge of 110 the plate or bar 33 and against one of the transverse plates or bars 28 and engaged by adjustable clamps 35. The clamps 35, which are adjustably secured to the lower faces of the bottom flanges of the side bars 27 of 115 the upper auxiliary frame by screws 36, have recessed engaging portions, which extend beneath the adjacent upper flanges of the transverse beams 11 of the main frame. When the screws 36 are tightened to engage 120 the jaws with the upper transverse beams 11, the upper auxiliary frame is firmly gripped thereon.

The machine is equipped at the front with a vertical magazine 37, adapted to receive a 125 stack 38 of material, which may consist of pieces of cut lumber, or any other material of a similar character, adapted to be handled in bulk and tied in bundles. The magazine, which may be constructed in any de-

130

sired manner, is illustrated in the drawings as consisting of outer fixed vertical bars 39 and inner adjustable vertical bars 40, adapted to be moved toward and from the outer fixed vertical bars to vary the size of the magazine. Each set of upper and lower auxiliary frames is equipped with a pair of these magazine-forming bars 39 and 40. The fixed outer vertical bar 39 is secured at its lower end to the front end of the upper channeled bar 15^a of the lower auxiliary frame, and the inner adjustable bar 40, which is arranged in the same longitudinal plane as the outer fixed bar 39, is provided at its end with a rearwardly extending horizontal arm 41, which is adjustably secured by bolts 42, or other suitable fastening devices to one of the angle bars 27 of the upper auxiliary frame (see Fig. 5). As shown in Figs. 1 to 3 inclusive, the inner vertical magazine bars 40 are arranged at the limit of their rearward movement to provide a bundle of the maximum width, and they are adapted to be adjusted forwardly from such position to decrease the width of the bundle. The inner adjustable magazine forming bars 40 terminate at the side bars 27 of the upper auxiliary frames to form an opening 43 at the lower portion of the inner side of the magazine 37 to permit the lower portion of the stack 38 to be advanced or moved rearwardly from the magazine into a bundle receiving space or chamber 44. The upper longitudinal channeled bars 15^a of the lower auxiliary frames constitute a support for the material; and the bundle, when formed by the feeding mechanism, about to be described, is moved along the channeled bars 15^a to a point beyond the magazine to the position illustrated in Fig. 3 of the drawings.

The feeding or bundle forming mechanism, which feeds the material from the bottom of the stack, comprises in its construction a lower longitudinally slidable horizontal bar 45, an inner vertical bundle engaging bar 46, a top horizontal stack supporting bar 47 and an outer vertical bar 48, extending upwardly from the outer end of the slidable bar 45 to the outer end of the top stack supporting bar 47. The lower horizontal bar 45, which constitutes a slide, operates in the groove or channel of the top longitudinal bar 15^a, which forms a guide for the said bar 45. The vertical bars 46 and 48 are suitably secured at their upper ends to the stack supporting bar 47, and their lower portions are adjustably connected to the slidable bar 45 by clamping plates 49, secured by bolts 50, or other suitable fastening devices to the bar 45 and adapted to clamp the bars 46 and 48 in vertical adjustment. By this construction, the effective length of the bundle forming bar 46 is varied to form a bundle of the desired height, and

the stack supporting bar 47 is raised and lowered to arrange it in proper position for supporting the stack left within the magazine during the feeding of the material in the formation of the bundle.

The inner or rear end of the slidable bottom bar of the feeding device is pivoted to the upper end of an inclined connecting link 51, Figs. 1 to 4, 8 and 9, extending downwardly and rearwardly from the slidable bar 45 and pivoted at its lower end to the upper end of a cam actuated lever 52. The cam actuated lever 52 is of angular form and when the feeding device is in its initial position, or at the limit of its outward or forward movement, as illustrated in Figs. 1 and 3 of the accompanying drawings, the upper portion of the lever 52 is arranged at an inclination and extends downwardly and rearwardly over a main transverse shaft 53 to a point in rear of the same, and when the lever is in such position its lower portion, which is arranged at an obtuse angle to its upper portion, extends downwardly and forwardly to a transverse pivot 54 upon which the lever 52 is mounted. The pivot 54 is arranged in a suitable bearing bracket 55, secured to the channeled bar 14 at the lower web or flange thereof. The transverse pivot 54 is located below and slightly in rear of the main transverse shaft 53, the angular shape of the lever 52 enabling the same to clear the shaft 53 in its backward and forward oscillation. The lever 52 is provided at its angle with a roller 56, Figs. 1, 2, 7 and 9 which is arranged in a cam groove 57 in the outer face of a cam disk or wheel 58, which, when rotated, oscillates the lever 52 to reciprocate the feeding device. At each revolution of the cam disk or wheel, the feeding device is moved inwardly or rearwardly a sufficient distance to carry the material at the bottom of the stack from the magazine into the bundle receiving chamber, and is moved forwardly to return it to its initial position after the bundle has been bound and tied. The cam groove 57 consists of similar opposite actuating portions to swing the lever 52, and an intermediate curved connecting portion arranged concentric with the pivot of the cam disk or wheel 58 for causing the lever 52 to dwell at the inner limit of its movement while the bundle is being bound and tied. The upper portion of the lever 52 is provided with a plurality of perforations 59, adapted to receive the rear pivot of the connecting link 51 to vary the length of the stroke of the feeding device, and while only two perforations 59 are shown in the drawings, any number may, of course, be employed.

In order to relieve the feeding device during its return movement from the weight of the stack, the latter is supported by a vertically movable stack supporting and charg-

ing device, which after the feeding device has returned to its initial position, lowers the stack to the bottom of the magazine and thereby arranges a charge of material in position to be operated on by the feeding device for forming the next bundle. Each stack supporting and charging device consists of a follower and comprises in its construction a top horizontal supporting bar 60, 5 Figs. 1 to 3 and 6, and a central vertical slidable bar 61 operating in the groove of a vertical channeled bar or post 62, secured at its lower portion to the lower channeled bar 14. The vertical channeled bar or post 62 10 is provided at its lower portion with opposite ears or flanges 63, which are bolted or otherwise secured to the channeled bar 14, and the channeled bar or post 62 is arranged so that the bar 61 of the stack supporting 15 and charging device is confined in the groove or channel by the bar 14.

The vertically movable stack supporting and charging devices are connected by links 64 with oscillatory arms 65 of a front transverse rock shaft 66, provided with a longitudinal groove or keyway 67 to receive keys for slidably interlocking the arms 65 with the shaft 66, whereby when the auxiliary frames are adjusted laterally, the arms 65 20 will be carried with them in their adjustment. The arms 65 extend rearwardly from the rock shaft 66, and the links 64 depend from the rear ends of the arms and the channeled posts 62 are provided with vertical 25 slots 68 through which pass the lower pivots 69 of the links 64, which connect the links with the vertically slidable bars 61. The front transverse rock shaft extends across the space between the side channeled beam 30 3 and the intermediate longitudinal channeled beam 4 and is mounted in front bearing brackets 70, bolted to the top flanges of the beams 3 and 4 and the said brackets may be braced in any suitable manner if 35 desired. The transverse rock shaft is provided at its outer end with a depending oscillatory arm 72, pivoted at its lower end to a block 73 having upper and lower openings 74 through which pass spaced upper 40 and lower rods 75, extending forwardly from the front end 76 of a substantially horizontal longitudinal bar or pitman 77. The rods 75, which are arranged in the same longitudinal plane as the bar or pitman 77 45 constitute an extension thereof and receive an adjustable block or abutment 78, arranged in spaced relation with the front end 76 of the bar or pitman 77 and adapted to be positioned different distances therefrom 50 to permit the bar or pitman 77 to have a limited movement independently of the arms 72 of the rock shaft for controlling the amount of movement imparted to the stack supporting and magazine charging device. 55 The adjustable block 78 is provided with

upper and lower openings 79 for the rods 75, and the outer portions thereof are provided with screw threads 80 for the reception of nuts 81, arranged in pairs to form a lock for securing the block 78 in its adjustment. 70

The horizontally disposed longitudinal bar or pitman 77 is provided at its rear portion with a longitudinal slot 82 through which passes the main transverse shaft 53, 75 forming a guide for the bar or pitman 77 and carrying a cam 83 for actuating the same. The rear end of the bar or pitman 77 is equipped with a roller 84, extending inwardly from the bar or pitman and arranged to be engaged by the cam 83. The cam 83, which is keyed or otherwise fixed to the main transverse shaft 53, tapers inwardly toward the shaft and has similar uniformly curved side edges 85 and a curved 80 outer edge 86, which is concentric with the shaft 53 to cause the bar or pitman 77 to dwell at the end of its inward or rearward movement to maintain the stack supporting and charging device in an elevated position, 90 while the feeding device is being returned to its initial position. One of the curved side edges 85 contacts with the roller 84 and moves rearwardly the bar or pitman 77, which in its forward movement is actuated 95 by the weight of the material within the magazine, the downward movement of the stack supporting and charging device and the consequent forward movement of the bar or pitman 77 being controlled by the other 100 curved side edge 85 of the cam 83, which in its rotary movement permits the stack to descend gradually to the bottom of the magazine. 105

The upper and lower right and left hand threaded screws, which adjust the upper and lower auxiliary frames and maintain the same in parallel relation and vary the length of the magazine, engage suitable nuts 86^a, 110 Fig. 4, of the said auxiliary frames and are mounted at their ends in upper bearing brackets 87 and in lower bearings 88 of the lower longitudinal beams 3 and 4 of the main frame. The upper bearing brackets are mounted on the upper longitudinal 115 beams 11 of the main frame, and the lower bearings 88 extend from opposite faces of the webs of the beams 3 and 4. Upper and lower sprocket wheels 89 and 90 are mounted on the outer ends of the screws, which have 120 reduced threaded inner terminals 91 receiving nuts 92 and washers 93, interposed between the adjacent bearings and the nuts, which are adjustable to take up any end motion of the right and left hand threaded 125 screws. The upper and lower sprocket wheels, which receive the end thrust at the outer ends of the upper and lower adjusting screws, mesh with and are connected by a sprocket chain 94, which also meshes with a 130

(3)

sprocket wheel 95, fixed to a rotary stub shaft 96, mounted in a bearing opening in the outer front column of the main frame of the machine, and provided at its inner end 5 with a collar 97, keyed or otherwise secured to the inner end of the shaft 96. The sprocket wheel of the front lower right and left hand threaded screw is located at a point in advance of the front upper 10 sprocket wheel, and the sprocket chain, which extends downwardly from the front upper sprocket wheel, passes beneath the sprocket wheel or pinion 95 and extends downwardly and forwardly at an inclination 15 to the lower front sprocket wheel. The sprocket wheel 95 is arranged at a point intermediate of the ends of the shaft 96 and is located at the outer face of the said column. The shaft 96 is provided at its outer end 20 with a suitable operating device preferably consisting of a crank handle 98, adjustably secured in a transverse opening in the said shaft 96 by a set screw 99. The sprocket 25 gearing is adapted to rotate simultaneously the right and left hand threaded screws, which move the upper and lower auxiliary frames laterally of the machine to space them and the mechanism carried by the frames the desired distance apart to suit the 30 length of the material to be bundled.

The bundles of the material formed by the feeding devices may be bound automatically by the mechanism hereinafter described, or by any other automatic binding and tying 35 mechanism, or they may be bound and tied by hand. In the automatic binding and tying means illustrated in the accompanying drawings, the wire 100 for each adjustable frame is fed from a reel 101, Fig. 33, detachably mounted on a rod 102, extending across 40 the inner or rear end of a swinging frame 103 and removably connected therewith to enable the reel to be readily placed in and removed from the machine. The swinging 45 frame 103, Figs. 1 to 4 and 12, is composed of spaced side bars, angularly bent at an intermediate point and laterally offset from each other to form a forked rear portion 104 of sufficient width to straddle the wire reel. 50 The front portions of the side bars are connected by bolts having supporting spacing sleeves, and the transverse rod 102 extends through and is supported by short transversely alined tubes or tubular journals 105, 55 see Fig. 33, screwed into openings in the sides of the forked portion of the swinging frame and supporting wheels 106, which operate in the guideways of the upper auxiliary frame, are supported in the space between the vertical tubes 31, which limit the 60 backward and forward movement of the swinging frame. The front end of the swinging frame is pivoted to a vertically movable needle bar 107, which is actuated 65 in its vertical movement through the up-

wardly and downwardly swinging movement of the frame 103, and the backward and forward movement of the swinging frame permits the latter to maintain itself in proper position with relation to the needle bar 107. 70

The wire from the reel extends between upper and lower grooved wheels 108 and 109, Fig. 34, of a tension device, which controls the feeding of the wire while the bundle is being bound. The upper grooved wheel is mounted in pivoted arms 110 and is held against the lower grooved wheel 109 by coiled springs 111, arranged on a pair of screws 112, Fig. 12, extending upwardly 80 from the side of the swinging frame at the front of the forked portion thereof and passing through openings in the rear ends of the pivoted arms 110 and having threaded upper portions for the reception of adjusting nuts 113, which engage the springs 111 and control the tension thereof. The arms 110 are pivoted at their front ends, and the lower wheel is mounted on a transverse shaft 114, journaled in suitable bearings of the swinging frame and extending from one side thereof and carrying a brake wheel 115, which co-operates with a brake band 116. The ends of the brake band extend forwardly from the brake wheel and are 90 pierced by a screw 117, fixed to and extending upwardly from the adjacent side of the swinging frame and equipped at its upper end with a nut 118, which engages a coiled spring 119 interposed between the nut and the upper end 120 of the brake band. The nut 118 controls the tension of the spring 119 and enables the brake to be applied with sufficient force to lock the lower grooved wheel 109 and thereby prevent unreeling or 100 feeding of the wire. The upper end 120 of the brake band is extended and projects over the rear portion of the upper face of a squared head 121 of a transverse pivot 122 (see Fig. 12), which connects the rear end 110 of a wire tensioning and take-up arm 123 to the swinging frame. The wire take-up and tensioning arm 123 is composed of spaced side bars, and is equipped at its front free end with a grooved guide wheel 124 115 over which the wire passes. The wire tensioning and take-up arm extends longitudinally of the front portion of the swinging frame and is adapted to swing upwardly and downwardly with relation to the same 120 to take up any slack in the wire and maintain the same under a constant pressure during the binding and tying operation, so that there is no slack or looseness in the band, which must be taken up by the expansion of 125 the bundle or package. The pivoted wire take-up and tensioning arm is urged upwardly away from the swinging frame by a coiled expandible compression spring 125, connected at its ends to front and rear 130

- blocks 126 and 127, pivoted, respectively, to the wire take-up arm and the swinging frame.
- The pivot 122 of the wire take-up arm 123 is rigid with the arm, and when the arm 123 swings downwardly and is arranged in close relation with the swinging frame, the rear upper corner of the rectangular head of the pivot engages the extended end 120 of the brake band and lifts the same against the action of the coiled spring 119 and relieves the brake wheel of pressure of the brake band and permits the unreeling or feeding of the wire to be controlled by the tension device. When, however, there is any slack in the wire, the take-up or tensioning arm 123 swings upwardly under the influence of the spring 125 and takes up the slack. This upward swinging movement of the wire take-up or tensioning arm lowers the rear upper corner of the rectangular head 121 of the pivot 122 and permits the spring 119 to force the brake band into engagement with the brake wheel and apply the brake and prevent further feeding of the wire until the wire take-up or tensioning arm is again swung downward in close proximity to the swinging frame and operates to release the brake.
- The pivot 128, which connects the upper end of the needle bar to the front end of the swinging frame, supports an upper grooved guide wheel 129, and the wire extends downwardly therefrom along the needle bar to a lower grooved guide wheel 130, mounted on a shaft 131, which is journaled in a tubular bushing 132, carried by the needle bar. When the feeding mechanism is in its initial position, as illustrated in Fig. 1 of the drawings, the needle bar is at the limit of its upward movement and the stack of material rests upon the front portions of the upper longitudinal channeled bars of the lower auxiliary frames, which constitute the bottom of the magazine. When the parts of the machine are in this position, the wire extends downwardly from the upper grooved guide wheel 129 of the needle bar to a bottom grooved guide wheel 133, located at the bottom of the magazine and mounted on a relatively fixed bracket 134, secured to and extending upwardly from the front of a housing or support 135 in which the wire coiling mechanism is mounted. The lower portion of the stretch of wire from the upper guide wheel 129 is located at the rear opening 43 of the magazine, and when the lower portion of the stack is advanced into the bundle receiving chamber by the feeding mechanism, the material constituting the bundle engages the said stretch of wire, the vertical portion at the opening 43 fitting against the rear face of the bundle and the wire constituting the top of the band is drawn from the reel as the bundle advances

into the bundle receiving chamber. Simultaneously with this operation, the wire constituting the bottom of the band is allowed to be fed to the bundle from a wire extension lever 136 to which the free end of the wire is attached, see Fig. 1, in a manner to be more fully described hereinafter, and which swings upwardly and rearwardly with the advancing movement of the bundle. By this arrangement, the wire is laid on the rear and upper and lower faces of the bundle without drawing the wire across the material, so that there is no liability of the material of the bundle being cut or otherwise injured in the binding operation thereof. The tension on the wire produces sharp bends at the upper and lower edges of the bundle at the back thereof, so that the wire is placed in a taut condition around the bundle and there will be no liability of any looseness of the band, and the bundle will be maintained in a tightly bound condition after the wire is knotted or tied. After the bundle has been advanced by the feeding mechanism to the limit of the rearward movement thereof to the position illustrated in Fig. 2 of the drawings, the wire is placed against the front face of the bundle by the needle bar, which moves downwardly from the position illustrated in Fig. 2 of the drawings to that shown in Fig. 3. This downward movement of the needle bar produces a sharp bend at the upper edge of the front of the bundle and forms a loop in the wire, the loop being composed of front and rear vertical portions and a bottom connecting bend or portion, which extends around the bottom of the lower grooved guide wheel 130, Fig. 27, of the needle bar. The inner or rear vertical side of the loop forms the front portion of the band, the wire being severed at the lower end of the front side of the loop, as hereinafter fully explained.

The swinging frame 103 is connected at a point intermediate of its ends, Fig. 1, to the upper end of a link 137, which is pivoted at its lower end to an arm 138 of a top transverse rock shaft 139, journaled in suitable bearings 140 and provided with a longitudinal groove or keyway 141, which receives keys for slidably interlocking the arms 138 with the upper transverse rock shaft 139. The arm 138, which is curved upwardly and forwardly from the rock shaft, is provided at intervals with perforations 142 to permit an adjustment of the swinging frame for arranging the same at different elevations to position the needle bar properly to correspond to any adjustment of the magazine and to suit the size of the bundles formed by the feeding mechanism. The bearings 140 are mounted on the upper longitudinal beams of the main frame of the machine, and the top rock shaft is provided at one end with an arm 143, which

is connected to the upper end of an upright actuating bar or pitman 144, provided at its lower portion with a slot 145 through which passes the main transverse shaft. The upper 5 right connecting bar or pitman is provided adjacent to the upper end of its slot 145 with a roller 146, which operates in a cam groove 147 in the outer face of a gear wheel 148. The cam groove is composed of inwardly 10 converging side portions and a connecting outer portion, which is arranged concentric with the main transverse shaft and located adjacent to the rim of the gear wheel. The converging side portions of the cam groove 15 147 extend inwardly from the ends of the peripheral concentric portions to a point slightly beyond the center of the gear wheel, and they actuate the upright bar or pitman in the upward and downward movements 15 thereof, and the concentric connecting portion of the cam groove permits the upright bar or pitman 144 to dwell at the limit of its upward movement, as clearly illustrated in Fig. 1 of the drawings, while the bundle 20 is being advanced by the feeding mechanism from the magazine to the rear bundle receiving chamber or space. The needle bar 107 is maintained in a vertical position by the needle bar guide 34 during the oscillation 25 of the swinging frame.

The wire extension lever 136, which is angular, is disposed longitudinally of the machine when it is at the limit of its downward movement, as illustrated in Fig. 1 of the drawings, and it is pivoted at its rear 30 end 149 to a depending web or portion of the housing or support 135, and it is adapted to swing upwardly therefrom to an upright position, as illustrated in Figs. 2 and 35 40 of the drawings. It is provided at an intermediate point in advance of its angle with an approximately V-shaped arm 150, extending upwardly from the lever when the latter is at the limit of its downward 45 movement and pivoted at its upper end to a sleeve 151 of a connecting rod 152, equipped with a tension device and extending rearwardly from the arm of the wire extension lever and pivoted at its rear end to a cam 50 actuated lever 153. A coiled spring 154 is arranged on the connecting rod 152 and is interposed between a rear nut 155 and the inner or rear end of the sleeve 151. This spring constitutes a yieldable means for 55 connecting the wire actuating means with the wire extension lever. The front portion of the connecting rod extends through the sleeve, which is provided with a longitudinal slot or opening 156 receiving nuts 157 en- 60 gaging screw threads of the front end of the connecting rod and arranged to abut against the end walls of the slot or opening for limiting the relative slidable movement of the sleeve and the connecting rod. A pair 65 of nuts is preferably employed to form a

lock, and the coiled spring 154 urges the sleeve forwardly or outwardly, and it is adapted to compensate for any variation in the cam movements and enables a full tension on the wire to be maintained at all 70 times. The cam actuated lever 153, which is approximately L-shaped, is mounted at its lower end on a transverse pivot 158, and it is adapted to swing backwardly and forwardly, and when at the limit of its forward movement, it extends upwardly from a point below and slightly in rear of the main transverse shaft 53 and then forwardly over the same, as clearly illustrated in Fig. 8 of the drawings. The pivot 158 is mounted 75 in a bracket 159, which is secured to the lower longitudinal channeled bar 15 of the auxiliary frame, and the lever 153 is provided at an intermediate point with a roller 160, which is arranged in a cam groove 161 in the outer face of a cam disk or wheel 162. The cam groove is composed of a curved outer peripheral portion and a transverse connecting portion, extending across the central portion of the outer face of the cam 80 disk and having opposite grooved portions adapted to actuate the wire extension lever and swing the same upwardly and downwardly. The curved peripheral portion maintains the wire extension lever in its 85 upright position adjacent to the support or housing 135 while the wire is being knotted or tied. Each lower auxiliary frame carries a pair of cam disks or wheels 58 and 162. The cam wheel 58 is provided 90 with an extended hub or sleeve 163, Fig. 9, having a key 164 to engage the groove and slidably interlock the cam wheel 58 with the main transverse shaft, and the hub 165 of the other cam 162 is fixed to the sleeve or hub 163, the two cams 58 and 162 being 95 maintained in fixed relation by the means for securing their hubs together.

When the wire extension lever swings downwardly and forwardly, the end 166 of the wire is looped substantially as shown in Fig. 27 around a projecting terminal portion of a pin 167 slidably mounted in a central opening 168 of a cylinder 169, constituting a rotary wire looping device, see Figs. 110 18 to 21. The cylinder is journaled in a bearing opening in a block or piece 170, which is secured to a head 171 formed integral with the outer end of the wire extension lever 136. The pin is maintained in 115 a projecting position by an approximately L-shaped spring 172, secured at one end to the outer face of the head 171 of the lever 136 and extending around one side of the latter and having its free end bearing 120 against a head 173, formed on the rear end of the slideable pin and provided with a beveled inner edge or face 174, arranged to be engaged by a slideable wedge 175. The wedge 175, which is slotted or bifurcated to 125

straddle the rear portion of the slidable pin, is formed integral with a rod 176, which is guided in an opening of an arm or guide 177, (see Fig. 19) mounted on and projecting from the outer portion of the wire extension lever and arranged in spaced relation with the head thereof, as clearly illustrated in Figs. 20 and 23 of the drawings. When the wedge is moved outwardly, the 10 slidable pin is moved inwardly and its projecting terminal portion withdrawn from the looped end 166, and when the wedge is moved inwardly, the pin is automatically returned to its projecting position by the 15 spring 172.

The rod 176 is provided at its inner end with a laterally projecting pivot 178, which is carried by the wire engaging lever into and out of a recess 179 in the front terminal of a forwardly extending arm of a bell crank lever 180, fulcrumed at its angle on the support or housing 135 by a suitable pivot 181. One of the arms of the bell crank lever 180 extends forwardly from the pivot, and 20 its other arm extends downwardly and rearwardly and is provided at its lower end with a roller 182, arranged to run on the periphery of the cam wheel 58, which is provided at its periphery with a tapered projecting 25 cam 183 of approximately triangular shape. When the cam 183 engages the depending arm of the bell crank lever 180, it swings the said depending arm forwardly and lifts the forwardly extending arm of the said lever 180 and moves the wedge outwardly and 30 withdraws the projecting end of the pin from the looped end 166 of the wire.

The end of the wire is looped around the projecting terminal of the pin 167 by a lug 40 184, projecting from the end of the cylinder and arranged at the periphery thereof in spaced relation with the projecting end of the pin and tapered, as clearly illustrated in Fig. 29 of the drawings, to coöperate 45 with a cutter 185 to shear off the wire at the lower end of the outer vertical portion of the loop formed by the needle bar. The cutter 185, which consists of a straight piece, is arranged at an angle to the cylinder 169, 50 as clearly shown in Fig. 15 of the drawings, and it is adjustably mounted in an opening 186 of the block or piece 170 by a set screw 187, and its outer end is tapered or beveled to form a cutting edge to coöperate with 55 the eccentric lug of the rotary cylinder 169. When the cylinder is rotated, the lug 184 is moved from the position shown in Fig. 29 of the drawings and is carried across the cutting edge of the cutter and the wire is 60 severed, the end of the outer vertical portion, connected with the needle bar, being carried around the projecting end of the pin 167 by the lug 184 to form the looped portion 166, which secures the free 65 end of the wire to the wire extension lever,

and the projecting pin is maintained in engagement with the looped terminal of the wire during the forward and return movements of the wire extension lever.

The cylinder or cylindrical body of the 70 rotary wire looper is provided at its rear end with an arm 188, pivoted to the upper end of a bar 189, extending longitudinally of the outer portion of the wire extension lever and slidably mounted at its inner end 75 in an opening of an arm or guide 190, carried by the wire extension lever and preferably formed integral therewith and extending therefrom at an angle thereto, as clearly shown in Fig. 20 of the drawings. The 80 connecting bar 189 is provided at a point intermediate of its ends with a laterally projecting pivot 191, which is carried into a recess 192 of an oscillatory arm 193 by the upward movement of the wire extension lever, (see Figs. 9, 10 and 19). The arm 193 extends forwardly from a transverse pivot 194, mounted in a suitable bearing at the rear face of the housing or support 135 and carrying a rearwardly extending arm 195. 85 The arms 193 and 195 are rigidly connected by the transverse pivot 194 and constitute a lever for moving the bar 189 inwardly and outwardly to oscillate the arm 188 and partially rotate the cylinder 169. The arm 90 195 is provided at its rear end with a roller 196, which operates in a cam groove 197 in the inner side face of the cam wheel 162. The cam groove 197 consists of a relatively long curved portion extending around the main transverse shaft in spaced relation thereto and concentric therewith, and a transverse connecting portion arranged to oscillate the arm 195. One side of the transverse connecting portion of the groove 100 moves the bar 189, Figs. 19, 20 and 23, outwardly and carries an arm 198 into engagement with a spring lever 199 for causing the same to press the outer vertical side of the needle formed loop into the channel or 105 space between the projecting terminal of the slidable pin 167 and the lug 184, which occurs after the horizontal terminal has been caught by an upwardly projecting lug 200 of a rotary coiler 201 and after the loop 110 166 of the horizontal terminal has been released, see Figs. 19 to 21 and 26. The other end of the transverse connecting portion of the cam groove 197 moves the bar 189 inwardly and swings the arm of the rotary cylinder 120 downwardly and actuates the cylinder to sever the wire and form the looped terminal 166 around the projecting end of the slidable pin. The central support of the transverse connecting portion of the cam 125 groove 197 is concentric with the main transverse shaft, and there is a pause between the outward and inward movements of the connecting bar 189. Also when the roller 196 of the arm 195 is in the long 130

curved concentric portion of the cam groove 197, the lever formed by the arms 193 and 195 is stationary.

The arm 198 is secured at one end to the connecting bar 189, and it is arranged in an approximately horizontal position when the wire extension lever is in an upright position, as illustrated in Fig. 23 of the drawings, and it is provided at its outer 10 end with a horizontal angularly disposed portion for engaging the spring lever 199. The spring lever 199, which is composed of an upper plate or piece and a lower resilient portion or spring 202, is fulcrumed on the bracket 134 by a horizontal bolt 203, which pierces a web or flange of the bracket and extends through the central portion of the lever 199. The lower resilient portion 202 of the lever 199 is bowed, as shown, and 15 when the arm 198 moves upwardly or outwardly, the said resilient portion 202 is compressed against the bracket 134, thereby swinging the upper portion of the lever outwardly and forwardly to carry the wire into 20 the channel or space of the rotary looping device. The spring lever 199 is returned to and maintained in its initial position by an approximately U-shaped spring 199^a, secured at one end to the bracket 134 and connected at its other end to the upper portion 25 of the spring lever 199.

The rotary looping device is locked against rotary movement, when the wire extension lever is swung downwardly and until the same returns to the housing or casing 135, by means of an angular lever 204, Figs. 13 to 21, pivoted at an intermediate point by a bolt 205 to the block or piece 170 and composed of inner and outer arms arranged 30 at an obtuse angle to each other, the outer arm being approximately vertical, and the inner arm being inclined when the wire extension lever is in an upright position. The outer arm is provided at its terminal with 35 an engaging tooth 206, which is moved automatically into engagement with a recess 207 of the rotary cylinder by a spring 208, when the wire extension lever swings downwardly away from the support or housing 135. The spring 208, which is curved, is secured at one end to the wire extension lever and is connected at its other end to the inner arm of the locking lever 204. When the wire extension lever swings upwardly, 40 the inclined arm projects rearwardly and is carried into engagement with the support or housing 135, whereby the tooth of the outer arm is swung out of engagement with the rotary cylinder. As the locking lever 204 is carried away from the support or housing 135, it is reengaged with the rotary looping cylinder.

The coiling device, which is moved backwardly and forwardly to carry it into and 45 out of its wire engaging position, consists of

a vertical cylindrical portion having a vertical wire receiving slot 209 and provided at the bottom with spur teeth 210, forming a pinion and meshing with an actuating gear 211. The vertical slot 209, which extends inwardly from the periphery to the center of the rotary wire coiler, receives the lower end of the inner vertical portion of the needle formed loop, which inner vertical portion constitutes the front portion of the band. 70 When the rotary wire coiling device is in its engaging position, the vertical wire, which passes through the slot 209, is arranged centrally of the said rotary coiling device, and the horizontal terminal of the 75 band extends across the top of the rotary coiling device, and the lug 200 is located at one side of the slot 209, as clearly illustrated in Fig. 26 of the drawings. The rotary coiling device is mounted in vertically aligned 80 bearing openings 212 in the front ends of a pair of spaced upper and lower horizontal plates 213, secured at their inner or rear ends to a vertical stem 214. The lower end of the cylindrical body of the rotary coiling 85 device projects below the teeth 210 thereof and forms a journal, which is arranged in the opening of the lower plate 213. The upper end of the stem 214, Fig. 22, is reduced to form a supporting shoulder 215 and is 90 threaded for the reception of a nut 216, which secures the horizontal plates to the stem, a spacing disk or plate 217 being interposed between the inner or rear ends of the horizontal supporting plates 213. The 95 wire coiling device moves downwardly to follow the lead of the coil 218, and for this purpose the vertical stem 214 is guided in a vertical socket or opening 219 of a vertical shaft 220 to the upper end of which the 100 gear 211 is keyed or otherwise secured. The coiling device, when coiling one end of a tying wire around the other wire, operates to begin the coiling by forming the first coil 105 against the bundle and continuing the coiling operation and receding from the bundle as the subsequent coils are made. The vertical shaft 220 is journaled in a suitable bearing of a slidable carrier 221 movable 110 backwardly and forwardly to carry the rotary coiling device to and from its operative position and guided by a pair of spaced longitudinally disposed horizontal rods 222, arranged at the upper portion of the housing 115 or support 135 and supported by the same. The horizontal plates 213 are guided at an intermediate point by a vertical guide 223, composed of spaced vertical sides formed integral with and extending upwardly from the front portion of the slidable carrier as 120 shown in Figs. 20 and 21.

The carrier 221 consists of a horizontal body portion having a central vertical extension and provided with spaced depending front and rear portions. The central body 125

portion is provided at opposite sides of the center with longitudinal openings, which receive the guide rods 222, and the shaft 220 is arranged in a central vertical bearing opening, which extends through the central extension of the carrier. The inner or rear depending portion of the carrier is connected by a pivot 224 to one arm of a bell crank lever 225, Figs. 10 and 19, fulcrumed at its angle on the casing or housing 135 by a bolt 226 and having a lower rearwardly extending arm provided with a roller 227, which operates in a cam groove 228 in the inner face of the cam wheel 58. The cam groove 228, Fig. 11, consists of a relatively large concentric portion and a transverse connecting portion, which actuates the roller to slide the carrier backwardly and forwardly. The gear 211, which is approximately semi-circular, has a toothed peripheral portion arranged spirally at a slight inclination and adapted when rotated to conform to the vertical movement of the wire coiling device without its teeth getting out of mesh with the pinion 210. Fixed to the lower end of the vertical shaft 220 is a horizontal pinion 229, which meshes with a vertical beveled gear 230, mounted on a short horizontal rock shaft 231, which is journaled in the depending portions of the carrier. The beveled gearing, which connects the vertical and horizontal shafts 220 and 231 of the slidable carrier, is arranged in the space between the said depending portions of the slidable carrier, and the rock shaft is provided at its inner or rear end with a crank arm 232, which is connected by a bar 233, Fig. 9, to a cam actuated lever 234, extending longitudinally of the machine and mounted at its rear end on a transverse pivot 235, which is arranged in the spaced bearing blocks 26. The cam actuated lever is provided at an intermediate point with a roller 236, which operates in a cam groove 237 in the inner side face of the cam wheel 58. The lower end of the connecting rod 233 is pivoted to the cam actuated lever 234 adjacent to the front end thereof, and the front end portion 238 of the lever 234 is arranged in an approximately horizontal position and is guided between a central depending web of the support or housing 135 and a vertical bar 239, which is secured to the said web at one of the side faces thereof. The lever 234 is swung upwardly and downwardly by the cam wheel 58, and motion is imparted to the rock shaft for actuating the gearing to rotate the gear wheel 211 and the coiling device in mesh with the same. The support or housing 135 is bolted or otherwise secured to the lower longitudinal channeled bars of the lower auxiliary frame, and the upper portion 240 of said support or housing is approximately U-shaped, being composed of a horizontal bottom portion and front and

rear sides extending upwardly from the bottom portion and receiving the slidable carrier between them.

The cam, which actuates the wire coiling device, imparts a slight initial movement to the same to bend the horizontal terminal portion of the wire at 241 (see Fig. 28) to prevent the same from slipping through the coiling device when the terminal loop 166 is released by the withdrawal of the projecting portion of the slidable pin of the rotary looping device, and as soon as the horizontal terminal portion of the wire is caught by the twisting device and is released by the rotary looping device, the outer vertical portion of the needle bar formed loop of the wire is pressed into the channel or space between the projecting pin and the lug of the rotary looping device by the spring lever 199. The bottom horizontal portion of the band or coil is locked around the front vertical portion in tight frictional engagement and in coiling the horizontal wire around the inner vertical wire, the coiling device is carried slightly beyond the position in which it is withdrawn from the wires and a slight retrograde rotation is imparted to it in order to free it from the wires and to enable it to be readily withdrawn from them when the slidable carrier is moved rearwardly. The cam groove 237, which actuates the lever 234, is shaped to impart these movements to the wire coiling device.

At the completion of the coil 218 and prior to the severing and looping of the outer vertical portion of the wire, the inner vertical portion is given a slight bend 242 at the lower end of the coil 218 to prevent the vertical wire from slipping through the same. This bend 242 is made in the wire by a wire tying lever 243 while the lower grooved guide wheel of the needle bar is still in the bottom of the needle formed loop. As soon as the bend 242 is made, the needle bar moves upwardly and the wire is cut, the lower terminal portion of the front vertical wire of the band being carried upwardly by the wire tying lever 243, Figs. 24, 25, 29, 30 and 31, to tuck the said lower end of the front vertical wire between the band and the bundle at a point above the coil, which is also bent upwardly against the bundle by the wire tying lever to arrange the coil out of the way and thereby prevent it from being injured in the handling of the bundle. The wire tying lever, which is approximately L-shaped, consists of a long upright arm and a short upper approximately horizontal arm, and it is pivotally connected at a point intermediate of its ends to a crank arm 244, and its lower end is guided in a vertical slot 245 in the support or housing 135. The short horizontal arm of the wire tying lever is provided with a grooved head 246, and the lower end of the lever is provided

with a projection 247, which extends into the vertical guiding slot 245. The crank arm 244 depends in a substantially vertical position when the wire tying lever is in its 5 initial position, and in the wire tying operation it makes one half of a revolution carrying the wire tying lever upwardly and moving the wire engaging head 246 thereof through the curved path indicated by the 10 dotted circles *a*, *b*, *c*, *d*, *e*, *f* and *g* in Fig. 24 of the drawings. This upward movement of the lever lifts the wire and carries the same from the position shown in Fig. 24 to the tied position shown in Fig. 25.

15 In order to enable the wire tying lever to pass readily between the band and the bundle, the front vertical portion of the band is forced outwardly from the bundle by an approximately L-shaped finger 248, 20 consisting of a straight inner portion and a slightly curved outer portion, arranged approximately at right angles to the straight inner portion and provided at the outer end with a shoulder 249 and having a tapered or 25 wedge-shaped terminal portion. The band engaging finger is swung upwardly from the position illustrated in full lines in Fig. 24 of the drawings to the dotted position shown in the said figure, and the wedge-shaped 30 terminal portion 250 is inserted between the band and the bundle, the wedge forcing the band outwardly from the bundle to provide a space for the uncoiled end of the band, and the shoulder 249 bearing against 35 the band and forming a stop or abutment for the same and preventing the band from being carried in the direction of movement of the wire tying lever by the latter, so that the end of the vertical portion of the wire 40 will be positively tucked between the band and the bundle. The wire tying lever and the band engaging finger are movable to a position in overlapping relation, as clearly illustrated in Fig. 25 of the accompanying 45 drawings, so that the uncoiled end of the band is securely fastened under the front vertical portion of the same where it will be firmly held by frictional engagement when the oscillatory finger is withdrawn.

50 The crank arm 244 is fixed to the front end of a horizontal crank shaft 251, journaled in bearings of the upper portion of the support or housing 135 and extending longitudinally of the same, and provided at 55 its rear end with a pinion 252, Figs. 10 and 11, meshing with a sector-shaped gear 253 having an arm or extension 254, piercing a crank pin to which is connected the upper end of a rod 255, which is connected at its 60 lower end to a longitudinally disposed cam actuated lever 256, extending longitudinally of the machine and mounted at its rear end on the pivot 235, which also supports the rear end of the cam actuated lever 234. The 65 lever 256 is provided intermediate of its

ends with a roller 257, which operates in a cam groove 258 formed in the inner face of the cam wheel 162. The connecting rod 255, which is approximately vertical, is pivoted at its lower end to the lever 256 at a point 70 near the front end thereof and the front end of the said lever 256 is guided between the central vertical web of the support or housing and a vertical bar 259, secured to one of the side faces of the web of the support or housing in spaced relation with the same by the fastening devices, which also secure the guide bar 239. The cam groove 75 258 of the cam wheel 162 is shaped to impart to the gear and the crank actuated wire 80 tying lever the movements heretofore described.

The band engaging finger 248 is mounted on the front end of a crank shaft 260, Fig. 10, journaled in suitable bearings of the 85 support or housing 135 and arranged horizontally in spaced relation with the crank shaft 251 and in parallelism with the same and provided at its rear end with a crank 261. The parallel longitudinal shafts 251 90 and 260 are arranged at opposite sides of the central upwardly extending bearing portion of the carrier, which is grooved at opposite sides to receive the said horizontal shafts 251 and 260, as clearly illustrated in Fig. 22 95 of the drawings. The crank 261 is connected by a substantially vertical connecting rod 262 with the front end of a longitudinally disposed cam actuated lever 263, mounted at its rear end on a suitable pivot 264 and provided at an intermediate point with a roller 265, which operates in a cam groove 266 in the inner side face of the cam wheel 162. The pivot 264 is mounted in suitable bearings and the lower end of the connecting rod 100 262 is pivoted to the lever 263 near the front end thereof, the front end of the said lever 263 being guided in the space between the central vertical web of the casing or housing and the said guide bar 259.

110 The machine may be driven by any suitable power, which is connected by a belt with a pulley 267, loosely mounted on a transverse driving shaft 268 journaled in suitable bearings 269 of the main frame and carrying a pinion 270, which meshes with the gear wheel 148. The bearings 269 are preferably mounted on the longitudinal beams 2 and 4 of the main frame, and the pulley 267 is connected with the driving shaft by a clutch 271, which may be of any preferred construction. The clutch 271 is connected with a handle or lever 272 fixed to a longitudinal shaft 273 from which depends an arm 274 having a projecting point 115 275, which is carried into the path of a lug 276 of the gear 148, when the pulley is clutched to the driving shaft. The lug 276 is tapered to present a beveled engaging face, 120 which is adapted to contact with the pro- 125 130

jecting point 275 of the arm 274 to throw the clutch automatically out of engagement with the driving wheel to stop the machine after the bundle has been tied. The depending 5 arm 274 is detachably secured to the shaft by a set screw or other suitable means, and it may be moved out of the path of the lug and the handle or lever may be secured in position for holding the clutch in engagement 10 with the pulley of the driving shaft when a continuous operation of the machine is desired. The shaft 273, which extends longitudinally of the machine, is journaled in suitable bearings of the main frame, and 15 the operating handle or lever is fixed to the front of the shaft and is located at the front end of the machine.

When the machine is continuously operated, the bound bundle is automatically ejected 20 from the machine at the back of the bundle receiving chamber by the bundle being formed, and the machine is equipped with an inclined skid 277, extending downwardly from the same at the back of the bundle receiving space or chamber.

The mechanism for forming and feeding bundles herein shown and described is claimed *per se* in a co-pending application filed by me Dec. 21, 1916, Serial No. 138,228, 30 and is claimed in this application only in so far as it co-operates or is combined with the binding and tying mechanism herein shown and described. In this specification, in order to avoid confusion, one of the binding 35 and tying mechanisms only has been specifically described, but as was pointed out above, there are two of these mechanisms which are operated simultaneously, the wires of which are simultaneously bent around the 40 bundles, as the latter are forced into the bundle receiving chamber. By utilizing a plurality of these bundle tying mechanisms, the work can be more quickly and better done.

45 What is claimed is:—

1. A machine of the class described including means for coiling one end of a wire around another, and means for bending the other end of the wire independently of the 50 coiled end upwardly and laterally at the outer end of the coil, whereby the two ends are secured together.

2. A machine of the class described including a rotary coiling device provided 55 with a slot arranged to receive one end of a wire, said device being also provided with means for engaging the other end of the wire and adapted when rotated to coil such end around the first-mentioned end, and 60 means for bending the latter at the outer end of the coil, whereby the two ends are connected.

3. A machine of the class described including a rotary coiling device having a 65 slot adapted to receive one end of a wire

band and provided with means for engaging the other end of the band for coiling the same around the first-mentioned end, and means for bending the latter at the outer end of the coil and for tucking the said first- 70 mentioned end under the band.

4. A machine of the class described including a rotary coiling device provided with a slot and adapted to receive one end of a band adjacent to one corner of a bundle, 75 said rotary coiling device being provided at one end with means for engaging the other end of the band for coiling the same around the first-mentioned end, and means for tucking the first-mentioned end beneath the 80 band.

5. In a machine of the class described, the combination with means for placing a band around a bundle with the terminals of the band at one of the lower corners of the bundle, 85 a rotary coiling device provided with a slot to receive one of the terminals of the band and having means for engaging the other terminal of the band to coil the same around the first-mentioned terminal, and 90 means for bending the first-mentioned terminal upwardly and for tucking the same beneath the band above the coil.

6. In a machine of the class described, the combination with means for placing a band 95 around a bundle with the terminals of the band arranged vertically and horizontally at one of the lower corners of the bundle, a rotary coiling device having a vertical slot to receive the vertical terminal of the band 100 and provided at the top with a projecting portion arranged to engage the horizontal terminal of the band for coiling the same around the vertical terminal, and means for bending the vertical terminal to prevent the 105 same from slipping through the coil.

7. A machine of the class described including a rotary coiling device having a slot opening through three faces thereof to receive one terminal of a band and provided 110 at one end with a projecting lug arranged to engage the other terminal of a band for coiling the same around the first-mentioned terminal, said coiling device being disposed for rotation beneath said other terminal of 115 the band at substantially right angles thereto, means for slidably mounting the coiling device to permit the same to follow the lead of the coil, and means for rotating the coiling device. 120

8. A machine of the class described including a rotary coiling device provided with means for engaging one terminal of a band for coiling the same around the other terminal thereof, said coiling device being 125 provided with a pinion, means for slidably mounting the coiling device to permit the same to follow the lead of the coil, and a gear meshing with the pinion and having its teeth arranged at an inclination so as to 130

rotate the coiling device without getting out of mesh with the pinion thereof.

9. A machine of the class described including a rotary coiling device having a pinion, a slidable support carrying the coiling device and adapted to permit the same to follow the lead of the coil, means for guiding the support, and an actuating gear meshing with the pinion and having an inclined spirally arranged rim and adapted to rotate the pinion without getting out of mesh with the same.

10. A machine of the class described including a rotary coiling device having a pinion, an actuating gear meshing with the pinion and having its rim inclined or spirally arranged, a stem slidably mounted at the center of the gear and provided with a support carrying the coiling device, and means for guiding the support in the sliding movement of the stem.

11. A machine of the class described including a rotary coiling device having a horizontal pinion, a vertical shaft provided with a longitudinal opening, a gear mounted on the shaft and meshing with the pinion and having its rim inclined and spirally arranged, a vertical stem slidable in the opening of the shaft and provided with a support carrying the coiling device, and a vertical guide receiving the support.

12. A machine of the class described including a rotary coiling device having a pinion, a gear meshing with the pinion, a crank shaft, gearing connecting the crank shaft with the said gear, and a cam actuated lever connected with the crank shaft for rotating the same.

13. A machine of the class described including a rotary coiling device having a horizontal pinion, a vertical shaft, a gear arranged at the upper end of the vertical shaft and meshing with the pinion of the coiling device, a horizontal crank shaft, gearing for connecting the crank shaft with the vertical shaft, and a cam actuated lever connected with the crank shaft for rotating the same.

14. A machine of the class described including a rotary coiling device having a pinion, a gear meshing with the pinion, a crank shaft, gearing for transmitting motion from the crank shaft to the said gear, a rotary cam, an oscillatory lever actuated by the cam, and means for connecting the lever with the crank shaft.

15. A machine of the class described including a rotary coiling device having a pinion, a gear meshing with the pinion, a crank shaft, gearing for transmitting motion from the crank shaft to the said gear, a rotary cam having a groove, a lever fulcrumed at its rear end and provided at an intermediate point with means to coact with the groove of the cam, and means for con-

nnecting the front end of the lever with the crank shaft.

16. A machine of the class described including a rotary coiling device having a pinion, a gear meshing with the pinion, a crank shaft, gearing for transmitting motion from the crank shaft to the gear, a rotary cam having a groove, a lever fulcrumed at its rear end and provided at an intermediate point with means for coacting with the groove of the cam, means for connecting the front end of the lever with the crank shaft, and guiding means receiving the said front end of the lever.

17. A machine of the class described including means for coiling one end of a wire around another, and a wire tying lever arranged to bend the uncoiled end of the wire to prevent the same from slipping through the coil.

18. A machine of the class described including means for coiling one end of a band around the other, and a wire tying lever provided with means for engaging the uncoiled end of the band, and means for actuating the wire tying lever to bend the uncoiled end of the band at the outer end of the coil and to tuck such uncoiled end under the band.

19. A machine of the class described including means for coiling one end of a band around the other, means for bending the uncoiled end and tucking the same under the band, and means for forcing the band outwardly to provide a space for the uncoiled end.

20. A machine of the class described including means for coiling one end of a band around the other, a wire tying lever provided with means for engaging the uncoiled end of the band, means for moving the lever to bend the uncoiled end and carry the same under the band, and means for forcing the band outwardly to provide a space for the uncoiled end.

21. A machine of the class described including means for coiling one end of a band around the other, a wire tying lever provided with means for engaging the uncoiled end of the wire, a crank element connected with the wire tying lever at a point intermediate of the ends thereof for actuating the same, and means for guiding the lever to cause the same to bend the uncoiled end of the band at the outer end of the coil and carry such uncoiled end under the band.

22. A machine of the class described including means for coiling one end of a band around the other, a wire tying lever provided at one end with means for engaging the uncoiled end of the band, a guide receiving the other end of the lever, and a crank element connected with the lever at an intermediate point and adapted to actuate the same to bend the uncoiled end at the

outer end of the coil and carry such uncoiled end under the band.

23. A machine of the class described including means for coiling one end of a band around the other, a wire tying lever slidably mounted at one end and provided at the other end with a projecting arm or portion having means for engaging the uncoiled end of the band, and means connected with the lever for oscillating the same to bend the said uncoiled end and carry the same under the band.

24. A machine of the class described including means for coiling one end of a band around the other, means for bending the uncoiled end and tucking the same beneath the band, and an oscillatory finger provided with means for forcing the band outwardly to provide a space for the uncoiled end.

25. A machine of the class described including means for coiling one end of a band around the other, means for bending the uncoiled end and for tucking the same under the band, and a movable finger provided with a tapered or wedge-shaped portion arranged to force the band outwardly to provide a space for the uncoiled end.

26. A machine of the class described including means for coiling one end of a band around the other, a wire tying lever provided with means for engaging the uncoiled end of the band, means for actuating the lever to bend the uncoiled end and carry the same beneath the band, and a movable finger provided with means for forcing the band outwardly to provide a space for the lever and the uncoiled end.

27. A machine of the class described including means for coiling one end of a band around the other, a wire tying lever having means for engaging the uncoiled end of the band, means for moving the lever to carry the said uncoiled end under the band, and a movable finger having a wedge-shaped portion to force the band outwardly and provided with a shoulder to form a stop or abutment for the band.

28. A machine of the class described including means for coiling one end of a band around the other, a wire tying lever provided with means for engaging the uncoiled end of the band, means for moving the lever to carry the said uncoiled end beneath the band, and a finger movable in the opposite direction from the lever and provided with means for forcing the band outwardly and having a shoulder to form a stop or abutment for the band, the finger and the lever being movable to a position in overlapping relation.

29. A machine of the class described including means for coiling one end of a band around the other, a wire tying lever provided with means for engaging the uncoiled end of the band, a shaft having a crank

element connected with the wire tying lever and arranged to actuate the same, a pinion mounted on the crank shaft, a gear meshing with the pinion and having a crank pin, a cam actuated lever, and means for connecting the latter with the crank pin of the gear.

30. A machine of the class described including means for coiling one end of a band around the other, a wire tying lever having means for engaging the uncoiled end of the band, a crank shaft having a crank element connected with and actuating the wire tying lever, a rotary cam, a lever actuated by the cam, and means for transmitting motion from the cam actuated lever to the crank shaft.

31. A machine of the class described including means for coiling one end of a band around the other, a wire tying lever provided with means for engaging the uncoiled end of the band, a shaft having a crank element connected with and actuating the wire tying lever, a rotary cam having a groove, a lever pivoted at one end and provided at an intermediate point with means for coacting with the groove of the cam, means for guiding the other end of the cam actuated lever, and means for transmitting motion from the same to the said shaft.

32. A machine of the class described including means for coiling one end of a band around the other, a wire tying lever provided with means for engaging the uncoiled end of the band, a shaft having a crank element connected with and actuating the wire tying lever, gearing connected with the shaft and having a crank pin, a cam, a lever actuated by the cam, and a rod connecting the cam actuated lever with the crank pin of the gearing.

33. A machine of the class described including means for coiling one end of a band around the other, a wire tying lever provided with means for engaging the uncoiled end of the band, a shaft having a crank element connected with the wire tying lever, a rotary cam, a lever actuated by the cam and pivoted at one end, a guide receiving the other end of the lever, gearing connected with said shaft and having a crank pin, and a rod connecting the cam actuated lever with the crank pin of the gearing.

34. A machine of the class described including means for coiling one end of a band around the other, means for tucking the uncoiled end of the band under the latter, an oscillatory finger provided with means for forcing the band outwardly to provide a space for the said uncoiled end, a crank shaft carrying the said finger, and cam actuated means for rotating the crank shaft.

35. A machine of the class described including means for coiling one end of a band around the other, means for tucking the uncoiled end of the band under the latter, an

oscillatory finger provided with means for engaging and forcing the band outwardly to provide a space for the uncoiled end, a crank shaft carrying the oscillatory finger, a cam 5 having a groove, a lever pivoted at one end and provided at a point intermediate of its ends with means for coacting with the groove, whereby the lever is actuated by the cam, and a rod connecting the cam actuated 10 lever with the crank shaft.

36. A machine of the class described including means for coiling one end of a band around the other, means for tucking the uncoiled end of the band under the latter, 15 an oscillatory finger provided with means for engaging the band to force the same outwardly to provide a space for the said uncoiled end, a cam having a groove, a lever pivoted at one end and provided at an intermediate point with means for engaging 20 the groove, guiding means receiving the other end of the lever, and means for transmitting motion from the cam actuated lever to the finger.

37. A machine of the class described including a rotary coiling device provided with means for coiling one end of a band around the other, a slidable carrier movable backwardly and forwardly to carry the coiling 25 device to and from the engaging position thereof, means for bending the other end of the wire to prevent the working of the same out of the coiled end, means mounted on the carrier for rotating the coiling device, and cam actuated means for reciprocating the carrier.

38. A machine of the class described including a rotary coiling device provided with means for coiling one end of a band around the other, a slidable carrier for moving the coiling device to and from its engaging position, means mounted on the carrier for rotating the coiling device, a bell crank lever having one arm connected with 40 the carrier, means for bending the other end of the wire independently of the coiled end, and a cam arranged to engage the other arm of the bell crank lever for reciprocating the carrier.

39. A machine of the class described including a rotary coiling device, a slidable carrier for moving the coiling device backwardly and forwardly, means mounted on the carrier for rotating the coiling device, 45 bending means coactive with the coiling device, a cam having a groove, and a lever pivoted at an intermediate point and having one arm connected with the carrier and provided at its other arm with means for coacting with the groove of the cam.

40. A machine of the class described including a reciprocatory carrier, a rotary coiling device carried by the carrier, gearing mounted on the carrier for rotating the

coiling device, bending means operative subsequent to the action of the coiling device, a crank element connected with the said gearing, a lever connected with the crank element, a bell crank lever connected with the carrier, and a cam having grooves for 65 70 actuating the said levers to reciprocate the carrier and rotate the coiling device.

41. A machine of the class described including a housing having spaced horizontal rods, a slidable carrier having openings receiving the rods, a vertical shaft extending through the carrier at the space between the rods, a gear mounted on the upper end of the shaft, a rotary coiling device carried by the carrier and meshing with the gear, 75 a bending device carried by said housing for action subsequent to the rotation of the coiling device, gearing connected with the lower end of the shaft for rotating the same, a rotary cam, and means actuated by the 80 cam for reciprocating the carrier and for actuating the gearing to rotate the vertical shaft.

42. A machine of the class described including a housing, a bending device carried by said housing, a carrier slidable horizontally in the housing, a vertical shaft mounted on the carrier, a gear secured to the shaft, a rotary coiling device carried by the carrier and meshing with the gear, horizontal shafts 90 95 mounted on the housing at opposite sides of the vertical shaft, a wire tying lever connected with one of the horizontal shafts, a band engaging finger mounted on the other horizontal shaft, and cam actuated means 100 for rotating the said shafts and for reciprocating the carrier.

43. A machine of the class described including a housing, a wire tying lever mounted on the housing at the front thereof, a band engaging finger also mounted at the front of the housing, a carrier mounted in the housing and movable backwardly and forwardly, a rotary coiling device carried by the carrier and movable toward and from the said lever and finger, and means for rotating the coiling device and for oscillating the lever and the finger for initially coiling one end of the band about the other and the subsequent bending of said other end to prevent the withdrawal of the same through the coil.

44. A machine of the class described, comprising means for supporting a wire reel, a wire guide so arranged as to be spaced from the supporting means, a wire extension lever movable toward and from the guide and provided with means for holding the end of a wire, means for feeding a bundle of material between the reel supporting 105 means and the extension lever against the wire to form the top, bottom, and back of the band, a vertically movable needle bar 110 115 120 125

- normally located above the path of movement of the bundle and movable downwardly to place the wire against the front of the bundle and complete the band, and 5 means for severing the wire and for connecting the ends of the band.
45. A machine of the character described, comprising a guide, a vertically movable needle bar, a swinging frame pivoted to the needle bar and slidably in said guide, means on the frame for holding a reel, and means carried by the swinging frame for maintaining the lead from the reel under a constant tension.
- 10 46. A machine of the class described including a reciprocatory needle bar, means for guiding the same, a slidably and pivotally mounted swinging frame connected with the needle bar, and means connected with the swinging frame for oscillating the same to actuate the needle bar.
- 15 47. A machine of the class described including a reciprocatory needle bar, a guide, a swinging frame pivotally and slidably mounted in the guide and pivotally connected to the needle bar, and actuating mechanism connected to the swinging frame for oscillating the same to reciprocate the needle bar.
- 20 48. A machine of the class described including a reciprocatory needle bar, guides, a swinging frame having spaced portions slidably and pivotally mounted in the guides, said swinging frame being connected with the needle bar, means carried by the swinging frame for mounting a reel between the said spaced portions, and actuating mechanism connected with the swinging frame for oscillating the same to reciprocate the needle bar.
- 25 49. A machine of the class described including spaced guides, an oscillatory frame having spaced portions provided with wheels mounted in the said guides, a removable reel supporting rod extending across the space between the said spaced portions and carried by the swinging frame, a needle bar pivoted to the swinging frame, and means for oscillating the swinging frame to reciprocate the needle bar.
- 30 50. A machine of the class described including a reciprocatory needle bar, a slidably and pivotally mounted swinging frame pivotally connected to the needle bar, a rock shaft having an arm connected with the swinging frame, and a cam actuated bar or pitman connected with the rock shaft for rotating the same.
- 35 51. A machine of the class described including a reciprocatory needle bar, a swinging frame pivoted to the same, a rock shaft having an arm, means for transmitting motion from the rock shaft to the swinging frame, a shaft, a reciprocatory bar or pitman pivoted at one end to the arm of the rock shaft and provided at the opposite end with a slot through which the shaft passes, and a rotary cam element mounted on the shaft and actuating the reciprocatory bar or pitman.
- 40 52. A machine of the class described including a reciprocatory needle bar, a swinging frame pivoted to the needle bar, a shaft, a rotary element mounted on the shaft and having a cam groove, a reciprocatory bar or pitman provided with a slot to receive the said shaft and having means for engaging the cam groove, and means for connecting the reciprocatory bar or pitman to the swinging frame.
- 45 53. A machine of the class described including a reciprocatory needle bar, a swinging frame pivoted to the needle bar, a shaft, a rotary element mounted on the shaft and having a cam groove, a reciprocatory bar or pitman provided with a slot to receive the said shaft and having means for engaging the cam groove, and a rock shaft having spaced arms, one of the arms being pivoted to the bar or pitman and the other being connected with the swinging frame.
- 50 54. A machine of the class described including a main frame, an auxiliary frame adjustably mounted on the main frame, a swinging frame carried by the auxiliary frame, a needle bar also mounted on the auxiliary frame and connected with and actuated by the swinging frame, a shaft mounted on the main frame, an arm slidably interlocked with the shaft and connected with the swinging frame, and means mounted on the main frame for rotating the said shaft.
- 55 55. A machine of the class described including a main frame, an auxiliary frame adjustably mounted on the main frame, upper and lower shafts journaled on the main frame, a swinging frame carried by the auxiliary frame, a needle bar connected with the swinging frame, a rotary cam element mounted on the lower shaft, a bar or pitman actuated by the cam element and connected with the upper shaft, and an arm slidably mounted on the upper shaft and connected with the swinging frame.
- 60 56. A machine of the class described including a vertically movable needle bar, a swinging frame pivoted at one end to the needle bar, means for slidably mounting the other end of the swinging frame, means carried by the swinging frame for maintaining the wire under a constant tension, a brake automatically controlled by the tension means.
- 65 57. In a machine of the class described, a needle bar, a swinging frame connected with and actuating the needle bar, a wire support, a wire take-up device mounted on the swinging frame for maintaining the wire under a

- constant tension, and a brake for the wire automatically operated by the wire take-up device. 65
58. A machine of the class described including a reciprocating needle bar, a swinging frame connected with the needle bar, a pivoted spring actuated wire take-up arm carried by the swinging frame for maintaining the wire under a constant tension, and a 10 brake automatically controlled by the said arm. 70
59. A machine of the class described including a movably mounted wire take-up device having means for yieldably holding it in engagement with the wire to maintain the latter under a constant tension, and a 15 brake for the wire arranged to be operated automatically by the wire take-up device. 75
60. A machine of the class described including an oscillatory wire take-up device comprising an arm movable inwardly and outwardly, and means for yieldably urging the arm outwardly to maintain the wire under a constant tension, a wire holding brake 20 extending into the path of the wire take-up device and arranged to be automatically actuated by the same. 80
61. A machine of the class described including a wire tension device having wheels 25 between which the wire passes, a brake connected with the tension device for preventing the feed of the wire, and a yieldably mounted wire take-up device movable inwardly and outwardly and adapted to maintain a constant pressure on the wire, and provided with means for automatically operating the brake to apply the latter when the wire is slackened and to release the 30 brake when the tension on the wire increases. 85
- 40 62. A machine of the class described including a wire tension device provided with relatively adjustable wheels between which the wire passes, a brake connected with the tension device and having a projecting operating portion, a pivotally mounted wire 45 take-up device adapted to maintain a constant tension on the wire and provided with means for engaging the operating portion of the brake to operate the latter automatically. 100
- 50 63. A machine of the class described including a wire tension device provided with relatively adjustable wheels between which the wire passes, a brake connected with the 55 tension device and having a projecting operating portion, and an oscillatory wire take-up device provided with a pivot having a head or portion movable into and out of engagement with the operating portion of 60 the brake, whereby the latter is automatically controlled by the wire take-up device. 105
64. A machine of the class described including a wire take-up device having yieldable means for moving it outwardly against 65 the wire to maintain the same under a constant tension, said take-up device being adapted to be forced inwardly by the wire, and means for automatically checking the feed of the wire, said means being arranged to be engaged by the inward movement of 70 the take-up device to release the wire, whereby the latter is fed under a constant predetermined tension. 75
65. A machine of the class described including a pivotally mounted wire take-up device provided with means for receiving and guiding the wire, a spring for urging the take-up device outwardly to maintain a constant tension on the wire, and means automatically operated by the take-up device 80 for checking the feed of the wire. 85
66. A machine of the class described including a swinging frame, a needle bar connected with the frame, and a wire take-up device consisting of an oscillatory arm pivotally mounted on and carried by the swinging frame, and a spring connected with the arm and with the swinging frame for urging the former against the wire to maintain the latter under a constant tension. 90
67. A machine of the class described provided with a wire take-up device comprising a pivotally mounted oscillatory arm provided with a guide wheel arranged to receive the wire, and a spring connected with the 95 arm for urging the same against the wire. 100
68. A machine of the class described including a needle bar, a swinging frame connected with the needle bar, and a wire take-up device comprising an arm pivotally mounted on the swinging frame and provided with wire guiding means, blocks pivoted to the swinging frame and to the arm, and a spring connected with the blocks and arranged to urge the arm against the wire. 105
69. A machine of the class described including a needle bar provided at its upper and lower ends with wire guiding means, a swinging frame slidably and pivotally mounted and connected to the needle bar, and means carried by the swinging frame 110 and arranged to engage the wire to maintain the same under a constant tension. 115
70. A machine of the class described including a vertically movable needle bar provided at its upper and lower ends with grooved guide wheels, a slidably and pivotally mounted swinging frame pivoted to the needle bar, mechanism connected with the swinging frame for actuating the same 120 and the needle bar, and guide means for a wire so as to feed the latter over the upper guide wheel. 125
71. A machine of the class described including a pivotally mounted wire extension lever provided with means for holding the end of the wire and adapted to draw the latter outwardly, a cam actuated lever, and

yieldable means for connecting the cam actuated lever with the wire extension lever.

72. A machine of the class described including an oscillatory wire extension lever

5 provided with means for engaging the wire and adapted to draw the same outwardly, a rotary element having a cam groove, a lever provided with means for engaging the groove and actuated by the cam, a connecting rod pivoted to one of the levers, a sleeve slidably mounted on the connecting rod and pivoted to the other lever, and a spring disposed on the connecting rod and yieldably engaging the sleeve.

10 73. A machine of the class described including an oscillatory wire extension lever provided with means for engaging the wire and adapted to draw the same outwardly, a rotary element having a cam groove, a

20 lever provided with means for engaging the groove and actuated by the cam, a connecting rod pivoted to one of the levers, a sleeve pivoted to the other lever and slidably on the connecting rod and provided with a slot,

25 means mounted on the connecting rod and operating in the slot to limit the relative sliding movement of the sleeve, and a spring mounted on the connecting rod and yieldably engaging the sleeve.

30 74. A machine of the class described including an oscillatory wire extension lever, means mounted on the lever for looping the end of the wire, means also carried by the lever for engaging the end of the wire when the same is looped, and means for releasing the wire.

35 75. A machine of the class described including an oscillatory wire extension lever, means carried by the lever for cutting the wire and looping one end thereof, and means also carried by the lever for engaging the looped end of the wire to enable the latter to be drawn outwardly by the lever.

40 76. A machine of the class described including means for looping the end of the wire, a movably mounted device having a projecting portion arranged to engage the looped end of the wire, and means for actuating the said device to release the wire.

45 77. A machine of the class described including a pin having a projecting portion, means for engaging the wire to loop the same around the pin, and means for releasing the wire from the pin.

50 78. A machine of the class described including a pin having a projecting portion, means for engaging the wire to loop the same around the pin, and means for sliding the pin to withdraw the projecting end thereof from the looped end of the wire.

55 79. A machine of the class described including a projecting wire engaging device, means for engaging the wire to loop the same around the said device, and a cutter

arranged in the path of the wire for severing the same.

80. A machine of the class described including a slidable pin having a projecting portion, a rotary looping device provided with means for engaging the wire to loop the same around the pin, and means for withdrawing the pin from the loop.

81. A machine of the class described including a relatively fixed cutter, a slidable wire engaging device having a projecting portion, a rotary looping device arranged to carry the wire against the cutter to sever the former and adapted to loop one end of the wire around the projecting wire engaging device, and means for withdrawing the latter from the loop of the wire.

82. A machine of the class described including a rotary wire looping device provided with projecting wire engaging means, a pin slidably mounted on the wire looping device and having a projecting portion arranged in spaced relation with the said projecting wire engaging means, means for rotating the said device to loop the wire around the pin, and means for sliding the pin to withdraw the same from the wire.

83. A machine of the class described including a rotary wire looping device having a central opening and provided at one end with a projecting lug, a pin slidable in the opening and having a projecting portion arranged in spaced relation with the said lug, means for rotating the said device to loop the wire around the pin, and means for sliding the pin to withdraw the same from the looped wire.

84. A machine of the class described including a rotary looping device having an opening and provided with a projecting wire engaging lug, a pin slidable in the opening and having a projecting portion arranged in spaced relation with the lug, means for rotating the looping device to loop the wire around the pin, a cutter arranged in the path of the wire, and means for drawing the pin from the looped wire.

85. A machine of the class described including a rotary cylindrical looping device having fixed and slidable means for engaging and looping the end of a wire, means arranged to receive the looped portion of the wire, a relatively fixed cutter arranged in the path of the wire for severing the same and means for releasing the loop from said device.

86. A machine of the class described, including a slidable wire engaging device, means for looping the wire around the said device, a movable wedge arranged to actuate the wire engaging device to withdraw the same from the loop of the wire, and means for operating the wedge.

87. A machine of the class described in-

cluding a slidable pin having a projecting portion, means for looping the wire around the projecting portion of the pin, a slidable rod provided with a wedge arranged to actuate the pin to withdraw the same from the loop of the wire, and a cam actuated lever for operating the rod.

88. A machine of the class described including a frame, an oscillatory wire extension lever, a slidable pin mounted on the lever, means for looping the wire around the pin, a rod provided with a wedge for actuating the pin to withdraw the same from the loop of the wire, and a cam actuated lever mounted on the frame and arranged in the path of the rod and adapted to engage and operate the rod.

89. A machine of the class described including a slidable wire engaging pin having a projecting portion at one end, a slidable wedge arranged at the other end of the pin to engage and move the same in one direction, a spring for moving the pin in the opposite direction, and means for looping the wire around the projecting portion of the pin.

90. A machine of the class described including a frame, an oscillatory wire extension lever, a wire engaging device movably mounted on the lever, means carried by the lever for looping the wire around the said device, mechanism mounted on the lever for withdrawing the said device from the loop of the wire, and actuating means mounted on the frame and arranged in the path of and adapted to engage the mechanism of the lever for operating the same.

91. A machine of the class described including a frame, an oscillatory wire extension lever, a wire engaging device movably mounted on the lever, means also mounted on the lever for looping the wire around the said device, a slidable rod carried by the lever and connected with and adapted to actuate the wire engaging device to withdraw the same from the loop of wire, and mechanism mounted on the frame and arranged in the path of and adapted to engage the said rod for actuating the same.

92. A machine of the class described including a frame, an oscillatory wire extension lever, a movable wire engaging device mounted on the lever, mechanism carried by the lever for actuating the wire engaging device to withdraw the same from engagement with the wire, an actuating lever mounted on the frame and arranged in the path of and adapted to engage with the said mechanism, and means mounted on the frame for oscillating the actuating lever.

93. A machine of the class described including a frame, an oscillatory wire extension lever, a movable wire engaging device mounted on the lever, mechanism carried by

the lever for actuating the wire engaging device to withdraw the same from engagement with the wire, an actuating lever mounted on the frame and having a recess arranged to receive and engage with the mechanism of the wire extension lever, and means mounted on the frame for oscillating the actuating lever.

94. A machine of the class described including a frame, a wire extension lever, a wire engaging device movably mounted on the wire extension lever, mechanism carried by the wire extension lever for actuating the wire engaging device to withdraw the same from engagement with the wire, an actuating lever mounted on the frame and arranged in the path of and adapted to engage with the mechanism of the wire extension lever, and a cam mounted on the frame and arranged to engage the actuating lever.

95. A machine of the class described including a frame, a wire extension lever, a wire engaging device movably mounted on the wire extension lever, mechanism carried by the wire extension lever for actuating the wire engaging device to withdraw the same from engagement with the wire, a bell crank lever mounted on the frame and having one arm arranged in the path of and adapted to engage with the said mechanism, and a rotary cam mounted on the frame and having a peripheral projecting portion arranged to engage the other arm of the bell crank lever.

96. A machine of the class described including a frame, a wire extension lever, a wire engaging device carried by the said lever, a looping device arranged to loop the wire around the said engaging device, mechanism mounted on the lever for actuating the looping device, and means mounted on the frame and arranged in the path of the said mechanism and adapted to engage with and actuate the same.

97. A machine of the class described including a frame, an oscillatory wire extension lever, a wire engaging device carried by the lever, a rotary looping device mounted on the lever and arranged to loop the wire around the engaging device and provided with an arm, a bar mounted on the lever and connected with the arm, an actuating lever mounted on the frame and arranged in the path of and adapted to engage with the bar, and means for oscillating the actuating lever.

98. A machine of the class described including a frame, an oscillatory wire extension lever, a wire engaging device carried by the lever, a rotary looping device mounted on the lever and arranged to loop the wire around the engaging device and provided with an arm, a bar movably mounted on the

lever and connected with the arm of the looping device and having a pivot, an actuating lever mounted on the frame and provided with a recess arranged in the path of 5 and adapted to engage with the pivot of the bar, and means mounted on the frame for oscillating the said actuating lever.

99. A machine of the class described including a frame, an oscillatory wire extension lever, a wire engaging device carried by the same, a rotary looping device arranged to loop the wire around the said engaging device, a bar mounted on the lever and connected with the looping device, an actuating 15 lever mounted on the frame and arranged in the path of and adapted to engage with the said bar, and a rotary cam having a groove engaging the actuating lever and adapted to oscillate the same.

100. A machine of the class described including an oscillatory wire extension lever, a wire engaging device carried by the lever, a rotary looping device mounted on the lever and arranged to loop a wire around the said 25 engaging device, a locking device carried by the lever and arranged to engage the looping device to hold the same against rotary motion, and means arranged in the path of the locking device and adapted to release the 30 looping device.

101. A machine of the class described including an oscillatory wire extension lever, a wire engaging device carried by the lever, a rotary looping device mounted on the lever 35 and arranged to loop a wire around the said engaging device, a pivotally mounted spring actuated locking lever carried by the lever and arranged to engage the looping device, and means arranged in the path of and 40 adapted to be engaged by the locking lever for releasing the looping device.

102. A machine of the class described including an oscillatory wire extension lever, a wire engaging device carried by the lever, a rotary looping device mounted on the lever and arranged to loop a wire around the said 45 engaging device, a pivotally mounted locking lever carried by the wire extension lever and provided with means for engaging the looping device and having a projecting arm, means arranged in the path of the arm for operating the locking lever to release the looping device, and a spring for urging the engaging portion of the locking lever toward 55 the looping device.

103. In a machine of the class described, the combination of means for placing a band about a bundle with the terminals of the band brought together, and mechanism operative to coil one terminal about the other and also to form a means outside the coil for preventing the other terminal slipping through said coil.

104. A machine of the class described in-

cluding a wire engaging device having a 65 projecting wire engaging portion, means for looping the wire around the said projecting portion, said means being provided with a wire engaging portion arranged in spaced relation with the said projecting portion to 70 form a wire receiving space or channel, and means for pressing the wire into the space or channel.

105. A machine of the class described including a wire engaging device having a 75 projecting wire engaging portion, means for looping the wire around the said projecting portion, said means being provided with a wire engaging portion arranged in spaced relation with the said projecting portion to 80 form a wire receiving space or channel, a lever normally spaced from the said wire engaging portions, and means for actuating the lever to move the wire into the said space or channel and return the lever to its 85 initial position.

106. A machine of the class described including a wire engaging device having a projecting wire engaging portion, means for looping the wire around the said projecting 90 portion, said means being provided with a wire engaging portion arranged in spaced relation with the said projecting portion to form a wire receiving space or channel, a lever normally spaced from the said wire 95 engaging portions, mechanism connected with the wire looping means for actuating the same and provided with means for oscillating the lever, and a spring for returning the lever to its initial position.

107. A machine of the class described including a rotary wire-looping device having a projecting lug, a wire engaging projection arranged in spaced relation with the said lug, a lever arranged to press the wire 105 into the space between the projection and the lug, a bar connected with the looping device and adapted to rotate the same and provided with an arm arranged to oscillate the lever, and means for actuating the said bar.

108. A machine of the class described including a frame, a wire engaging lever mounted on the frame, an oscillatory wire extension lever movable toward and from the said lever, means mounted on the wire 115 extension lever for looping the wire, and mechanism carried by the wire extension lever for operating the wire looping means and for engaging the first-mentioned lever to cause the same to move the wire into engagement with the said looping means.

109. A machine of the class described including a frame, a rotary looping device having a projecting lug, a pin projecting from the looping device in spaced relation 125 with the lug, a bar connected with the looping device for rotating the same and provided with an arm, means for actuating the

- said bar, and a lever mounted on the frame and arranged to be engaged and oscillated by the arm of the bar, whereby the lever of the frame is actuated to move the wire into the space between the pin and the lug. 65
110. In a machine of the class described, the combination of means for placing a band around a bundle, means for coiling or wrapping one end of the band around the other, and means for bending the uncoiled end of the band at a point beyond the coil to prevent it from slipping through the same and for also bending the coil into the plane of and in close proximity to the bundle. 70
111. In a machine of the class described, the combination of means for placing a band around a bundle with the terminals of the band at one of the corners of the bundle, a rotary coiling device having a slot to receive one of the terminals of the band and provided with means for engaging the other terminal of the band to coil the same around the first-mentioned terminal, and means for tucking the first-mentioned or uncoiled terminal between the band and the bundle. 75
112. A machine of the class described including a rotary coiling device constructed to receive one terminal of a band through its periphery to a point centrally thereof and provided with means arranged to engage the other terminal of the band for coiling or wrapping the same around the first-mentioned terminal, said rotary coiling device being also movable in a direction longitudinally of the coil so as to follow the lead of the said coil, and means for rotating the coiling device. 80
113. A machine of the class described including a rotary coiling device having a slot to receive one terminal of a band and provided with means for engaging the other terminal of the band to coil or wrap the same around the first-mentioned terminal, said coiling device being movable in a direction longitudinally of the coil so as to follow the lead of the same, and means for bending the uncoiled terminal beyond the coil. 85
114. A machine of the class described including a rotary coiling device having a pinion and also movable in a direction longitudinally of its axis of rotation so as to follow the lead of a coil in making the same, and an actuating gear having its teeth set at an inclination or spirally arranged, whereby it is adapted to rotate the pinion without getting out of mesh with the same. 90
115. A machine of the class described including means for coiling one end of a band around the other, and a wire tying lever provided with means for engaging the uncoiled end of the band, and means for actuating the wire tying lever to tuck the uncoiled end of the wire under the band. 95
116. A machine of the class described including means for coiling one end of a band around the other, means for tucking the uncoiled end under the band, and means for engaging the band to prevent the same from moving with the tucking means. 100
117. A machine of the class described including means for coiling one end of a band around the other, means for tucking the uncoiled end under the band, and means for forcing the band outwardly to provide a space for the uncoiled end, the latter means also having an engaging portion for preventing the band from moving in the direction of the tucking means. 105
118. A machine of the class described including means for coiling one end of a band around the other, means for tucking the uncoiled end under the band, and a movable finger provided with means for forcing the band outwardly to provide a space for the uncoiled end and having a shoulder for engaging the band to prevent the same from moving with the said means for tucking the wire under the band. 110
119. A machine of the class described including means for coiling one end of a band around the other, means for tucking the uncoiled end under the band, and a movable finger provided with a tapered or wedge-shaped portion to force the band outwardly to provide a space for the uncoiled end of the band and having a shoulder arranged to engage and form a stop for the band to prevent the same from moving with the said tucking means. 115
120. A machine of the class described including means for coiling one end of a band around the other, a wire tying lever provided with means for engaging the uncoiled end of the band, means for moving the lever to carry the uncoiled end beneath the band, and a finger movable in the opposite direction from the lever and provided with an engaging portion arranged to form a stop for the band, the finger and the lever being movable to a position in overlapped relation. 120
121. A machine of the class described including means for coiling one end of a band around the other, a wire tying lever provided with means for engaging the uncoiled end of the band, means for moving the lever to carry the said uncoiled end beneath the band, and a finger movable in the opposite direction from the lever and provided with a tapered or wedge-shaped portion for forcing the band outwardly to form a space for the said uncoiled end of the band and having a shoulder arranged to engage and form a stop for the band to prevent the same from moving with the wire tying lever. 125
122. A machine of the class described including a rotary coiling device provided with means for coiling one end of a wire around another, a slid able carrier movable

- backwardly and forwardly to carry the coiling device to and from its engaging position, means for rotating the coiling device, means for actuating the said carrier and means for fixing the other end of the wire relative to the coil. 65
123. In a machine of the character described, means for placing a band about a bundle with the terminals of the band brought together and crossing each other, means operative to twist one terminal about the other, and means for bending the other terminal upwardly between the bundle and the band. 70
124. A machine of the class described including a rotary coiling device provided with means for coiling one end of a band around the other, a carrier movable backwardly and forwardly to carry the coiling device to and from its engaging position, a wire tying lever provided with means for engaging the uncoiled end and movable to tuck the same beneath the band, and a band engaging finger provided with means for forcing the band outwardly to form a space for the said uncoiled end. 75
125. A machine of the class described including a reciprocatory needle bar, a slidably and pivotally mounted swinging frame connected with the needle bar, means carried by the swinging frame for maintaining a wire under a constant tension, and means connected with the swinging frame for actuating the needle bar. 80
126. A machine of the class described including a reciprocatory needle bar, means for guiding the same, a slidably mounted swinging frame connected with the needle bar, and means for actuating the needle bar. 85
127. A machine of the class described including a reciprocatory needle bar, mechanism connected with the needle bar for actuating the same, and means carried by the said mechanism for maintaining a wire under a constant tension. 90
128. A machine of the class described including a reciprocatory needle bar, mechanism connected with the needle bar for actuating the same, means carried by the said mechanism for maintaining the wire under a constant tension, and a brake for the wire automatically controlled by the tension means. 95
129. A machine of the class described including a reciprocatory needle bar, mechanism connected with the needle bar for actuating the same, means carried by the said mechanism for maintaining a wire under a constant tension, and brake mechanism automatically controlled by the tension means. 100
130. A machine of the class described including a reciprocatory needle bar, mechanism for actuating the same, means for maintaining a wire under a constant tension, 65
- and brake mechanism automatically controlled by the tension means and adapted when applied to prevent feeding of the wire. 70
131. A machine of the class described including a reciprocatory needle bar, mechanism connected with the needle bar for actuating the same, a spring actuated wire take-up device for maintaining a wire under a constant tension, and a brake for the wire automatically operated by the said wire take-up device. 75
132. A machine of the class described including a reciprocatory needle bar, mechanism for actuating the same, a pivoted spring actuated wire take-up arm for maintaining the wire under a constant tension, and a brake for the wire automatically controlled by the said arm. 80
133. A machine of the class described including brake mechanism for controlling the feeding of a wire, and means for automatically operating the brake to release the wire when there is a predetermined tension on the same and for applying the brake when the wire slackens and the tension thereon decreases. 85
134. A machine of the class described including a wire tension device having wheels between which the wire passes, a brake connected with the tension device for preventing the feeding of the wire, and means controlled by the tension on the wire for automatically operating the brake to release the wire when there is a predetermined tension on the same and to apply the brake when the wire slackens and the tension thereon decreases. 90
135. A machine of the class described including a reciprocatory needle bar, mechanism connected with the same for actuating the needle bar, a take-up device for maintaining a wire under a constant tension, and an oscillatory extension lever provided with means for holding the end of the wire and adapted to draw the latter outwardly. 105
136. A machine of the class described including a reciprocatory needle bar, mechanism connected with the needle bar for actuating the same, a pivoted spring actuated wire take-up arm for maintaining a wire under a constant tension, and an oscillatory wire extension lever provided with means for holding the end of the wire and adapted to draw the latter outwardly. 110
137. A machine of the class described including an element movable backwardly and forwardly for drawing the wire outwardly, means mounted on the said element for looping the end of the wire, means also carried by the said element for engaging the end of the wire when the same is looped, and means for releasing the wire. 115
- 120

138. A machine of the class described including means for cutting the wire and for looping one end thereof, and means for engaging the looped end of the wire and for drawing the latter outwardly. 5
139. A machine of the class described including means for cutting the wire and for looping one end thereof, means for engaging the looped end of the wire and for drawing the latter outwardly, and means for releasing the wire. 10
140. A machine of the class described including a rotary looping device arranged to loop one end of the wire, means for engaging the looped end of the wire and for drawing the wire outwardly, and a locking device for holding the looping device against rotary movement while the wire is being drawn outwardly. 15
141. A machine of the class described including a movable element, a rotary looping device mounted on the said element for looping one end of a wire, means also carried by the said device for engaging the looped end 20 of the wire, means for moving the said element to draw out the wire and to feed the drawn out portion to a bundle, and a locking device for holding the looping device against rotary movement while the said element is in motion. 25
142. A machine of the class described including a wire looping device having an engaging portion, a relatively fixed wire engaging device arranged in spaced relation 30 with the engaging portion of the looping device to form a space or channel, means for moving the wire into the said space or channel, and means for rotating the looping device to loop the wire around the said relatively fixed engaging device. 35
143. A machine of the class described including a wire looping device having an engaging portion, a relatively fixed wire engaging device arranged in spaced relation 40 with the engaging portion of the looping device to form a space or channel, means for moving the wire into the said space or channel, means for rotating the looping device to loop the wire around the said relatively fixed engaging device, and means for moving the wire engaging device from its engaging position to release the looped end of the wire. 45
144. A machine of the class described including means for cutting and looping one end of a wire, means for engaging the looped end of the wire to hold the same, and a coiling device provided with means for engaging and coiling the looped end of the wire. 50
145. A machine of the class described including means for cutting a wire and for looping one end thereof, means for engaging the looped end of the wire for drawing the latter outwardly, and a coiling device 55
- movable toward and from the looped end of the wire and provided with means for engaging and coiling or wrapping the same around another portion of the wire. 60
146. A machine of the class described including means for cutting a wire and for looping one end thereof, an element carrying the latter means and movable backwardly and forwardly to draw the wire outwardly, and a coiling device movable toward and 70 from the said element and provided with means for engaging and coiling the looped end of the wire. 75
147. In a machine of the character described, means for placing a band around a bundle with the terminals of the band brought together, means operative to twist one terminal about the other, and means for bending the other terminal to prevent its slipping through the coiled terminal. 80
148. In a machine of the character described, means for placing a band around a bundle with the terminals of the band brought together, means operative to twist one terminal about the other, means for bending the other terminal to prevent its slipping through the coiled terminal, and means for severing the wire in the required length. 85
149. In a machine of the class described, spaced apart frame members forming a chamber therebetween, means mounted on one frame member for extending a wire therefrom to the other frame member across the front of said chamber, means upon the 90 said other frame member for holding the free end of the wire, means for pushing a bundle against said wire into said chamber whereby the bundle is inclosed by wire on the top, bottom and back, means for inclosing the front of said bundle with said wire, and means for tying said wire around the bundle. 95
150. In a mechanism of the character described, means for feeding wire, means for holding the free ends of the wires to present vertically extending strands thereof between the feeding means and the holding means, means for pushing a bundle against said vertically extending strands causing said 100 wires to inclose the top, bottom and back of said bundle forming bands, means for moving sections of the wire down in front of said bundle, and means for tying each of said bands. 105
151. In a mechanism of the character described, upper and lower frames spaced apart forming a bundle receiving chamber therebetween, reels mounted upon the upper of said frames, for extending wire from 110 said reels down in front of said bundle receiving chamber, means upon the lower frame member for holding the free ends of said wire, tensioning devices upon the upper frame for holding the wires taut, means for 115
- 120
- 125
- 130

shoving a bundle against said wires and into said bundle receiving chamber, whereby bands of wire are wrapped about the top, bottom and back of said bundle, means for 5 moving down strands of wire in front of said bundle completing the bands, means for tying each of said bands to the bundle, and means for severing the wires.

152. In a machine of the character described, means for feeding wire across the 10 path of movement of a bundle of material forwardly and rearwardly of the same when moved, means for moving the material to bring said wire into loop formation about 15 said material, and means for uniting the stretches of the wire at the point of crossing of the same.

153. In a machine of the character described, means for feeding wire across the 20 path of movement of a bundle of material forwardly and rearwardly of the same when moved, means for moving the material to bring said wire into loop formation about 25 said material, means for uniting the stretches of the wire at the point of crossing of the same, and means for severing the wire beyond the point of uniting of its stretches together.

154. In a machine of the character described, the combination with a bundle forming 30 mechanism having a stationary upright frame, of a plurality of wire tying mechanisms carried by and located within said frame, means for adjusting said wire tying 35 mechanisms toward and from each other, as well as toward and from the frame, and means for actuating said mechanisms.

155. In a machine of the character described, the combination with a bundle forming 40 mechanism having a fixed upright frame, of a plurality of movable wire tying mechanisms in the form of individual units carried by and located within said frame above the bundle to be tied, and means for 45 adjusting the positions of said wire tying mechanisms toward and from each other, as well as toward and from the frame, so as to place the desired number of wire bands around the bundle at desired intervals.

156. In a machine of the character described, the combination with an upright stationary frame, and a bundle forming mechanism mounted thereon and including a bundle-receiving chamber or support, of a 50 plurality of movable wire tying mechanisms carried by said frame above said chamber or support, means for actuating said wire tying mechanisms, and means for moving said wire tying mechanisms toward and from each other independently of said frame, so as to adjust the positions of the same and place the desired number of wire bands around the bundles at desired intervals.

157. In a machine of the character described, the combination with an automatic

bundle forming mechanism having a fixed upright frame, of a plurality of movable wire tying mechanisms including the wire reels, in the form of individual units carried by and located within said frame above the 70 bundle to be tied, and means for simultaneously moving said wire tying mechanisms toward and from each other thereby adjusting the positions of the same so as to place the desired number of wire bands around 75 the bundle at desired intervals.

158. The combination with the main frame, of a plurality of laterally adjustable upper and lower auxiliary frames, mechanism for forming the bundles, placing the 80 bands around the bundles and tying the ends of the bands carried by said auxiliary frames, and means for simultaneously moving said auxiliary frames toward and from each other.

159. A tying mechanism for tying bundles comprising a coiling device for coiling one end of one wire around the other wire with the first coil formed against the bundle, and means acting on said coiling device to cause 90 it to recede from the bundle as the subsequent coils are made.

160. In a tying machine for forming a tie around a bundle, a coiling device for coiling one end of a tying wire around the other 95 wire, said device operating to begin the coiling operation by forming the first coil against the bundle, said coiling device continuing the coiling operation and receding from the bundle as the subsequent coils are 100 made and including means for bending the end of the uncoiled wire laterally relative to the coils at the end of the coiling operation.

161. A machine of the character described, comprising wire extension means, having 105 means for holding the end of the wire, and adapted to draw the wire outwardly, means for actuating the wire extension means, and yieldable means for connecting the wire actuating means with the wire extension 110 means.

162. A machine of the character described, comprising a wire tension device, a brake connected with the tension device for preventing the feed of the wire, and means for 115 regulating the pressure on said device.

163. The combination with a bundling machine, of mechanism for directing a wire about a bundle, and tensioning said wire during the directing thereof, and mechanism 120 for coiling a portion of one stretch of the wire about a second stationary stretch thereof, the coiling being initially started against the bundle and formed outwardly therefrom.

164. The combination with a bundling machine, of mechanism for directing a wire about a bundle, and tensioning said wire during the directing thereof, mechanism for coiling a portion of one stretch of the wire 130

about a second stationary stretch thereof, the coiling being initially started against the bundle and formed outwardly therefrom, and means for severing the wire beyond the coils.

165. The combination with a bundling machine, of mechanism for directing a wire about a bundle, and tensioning said wire during the directing thereof, mechanism for 10 coiling a portion of one stretch of the wire about a second stationary stretch thereof, the coiling being initially started against the bundle and formed outwardly therefrom, means for severing the wire beyond the coils, 15 and means for distorting the uncoiled end of the wire to prevent the pulling of the same through the coils.

166. The combination with bundling mechanism, of means for drawing out a 20 sufficient amount of wire before a bundle is being bound to permit enveloping the bundle, and tensioning the wire during such operation, means for moving the bundle to cause the taut wire to be laid on the bundle 25 without drawing the wire across any of the faces of the bundle, and mechanism for tying the tensioned wire about the bundle.

167. The combination with a bundling machine, of means for first drawing out a

sufficient amount of wire before a bundle is 30 bound to permit enveloping the bundle, means for moving the bundle so as to cause the taut wire to be laid across three sides of the bundle without drawing the wire across any of the faces of the bundle, means for extending the wire along the remaining side of the bundle, means for tying the wire, and means for keeping the working length of the wire under constant tension during the entire operation.

168. A machine of the character described including a wire tension device, a brake connected with the tension device for preventing the feeding of the wire, and means controlled by the tension on the wire for automatically operating the brake to release the wire when there is a predetermined tension on the same and to apply the brake when the wire slackens and the tension thereon decreases.

In testimony that I claim the foregoing as my own, I have hereto affixed my signature in the presence of two witnesses.

JAMES M. LEAVER, Jr.
